UNITED STATES PATENT OFFICE.

JOTHAM B. TAYLOR, OF AUBURN, NEW YORK.

LIFTING-JACK.

No. 911,089.

Specification of Letters Patent.

Patented Feb. 2, 1909.

Application filed November 7, 1908. Serial No. 461,572.

To all whom it may concern:

Be it known that I, JOTHAM B. TAYLOR, of Auburn, in the county of Cayuga, in the State of New York, have invented new and useful Improvements in Lifting-Jacks, of which the following, taken in connection with the accompanying drawings, is a full, clear and exact description.

This invention relates to certain improvements in lifting jacks involving the use of a tubular supporting base threaded internally for receiving a hollow screw which in turn is also threaded internally for receiving a second screw of opposite pitch carrying at its upper end a suitable axle rest while the upper end of the hollow screw is provided with a ratchet wheel adapted to be rotated by a reversible pawl mounted upon an operating lever which in turn is journaled upon the upper end of the hollow screw directly under the ratchet wheel.

My main object is to reduce the number of parts necessary to the perfect operation of the lifting jack and to also reduce the size and weight to adapt the device for use as an automobile jack which may be conveniently carried in the machine without adding materially to its weight.

Another object is to provide a single reversible pawl slideable axially in the handle or lever and provided with a radially projecting hand piece moving in a transverse slot in the handle or lever and adapted to interlock with shoulders thereon.

Other objects and uses relating to specific parts of the device will be brought out in the following description.

In the drawings—Figure 1 is a side elevation of my improved lifting jack. Figs. 2, 3 and 4 are sectional views taken respectively on lines 2—2, 3—3 and 4—4, Fig. 1.

This jack comprises an upright tubular supporting standard —1— having a suitable supporting base —2— and an upper reduced end —3— which is threaded internally for receiving a hollow screw —4—, the greater portion of the interior of the upright —1— below the reduced portion —3— being of greater diameter than the exterior diameter of the screw —4— so as to reduce the weight of said upright and at the same time to reduce the length of the upper threaded end —3— thereby reducing the friction incidental to the operation of the screw —4—.

The upper end of the screw —4— is provided with a ratchet wheel —5— preferably

integral therewith and comparatively shallow vertically to permit a maximum vertical movement of a coaxial screw —6— which telescopes with the screw —4— and engages an internally threaded portion —7— in the upper end of said screw —4— and central portion of the ratchet wheel —5—. This internally threaded portion —7— of the screw —4— extends downwardly from the upper face of the ratchet wheel —5— a comparatively short distance considerably less than the length of said screw —4—, the greater portion of the interior of which is of somewhat larger diameter than the external diameter of the screw —6— to reduce the weight of the screw —4—.

The external thread of the screw —4— extends from the lower end thereof to the under side of the ratchet wheel —5— to permit the use of the jack without the operating lever and pawl hereinafter described and thereby obtain an increased vertical adjustment of the screw portions of the jack as it is evident that the ratchet wheel may be used as a hand wheel for moving the screws vertically relatively to the upright section —1—. Ordinarily, however, I prefer to use an operating lever —8— having at one end a tubular bearing —9— journaled upon the upper end of the screw —4— directly under the ratchet wheel —5— while the opposite end of said lever is provided with a tubular extension —10— for the reception of a handle if desired.

The intermediate portion of the lever —8— is provided with an upwardly projecting lug —11— and a vertical slot —12— extending downwardly from its upper face, said slot having opposite forward extensions —13— cut into the rear side of the lug —11— forming opposed shoulders —14—. This lug —11— and portion of the lever —8— at the rear side of the slot —12— are formed with circular bores or coaxial openings —15— and —16— communicating with the slot —12— for the reception of a pawl —17— and actuating spring —18— respectively. The pawl —17— is made in the form of a straight locking bolt extending through the opening —15— and having its front end movable into and out of engagement with the teeth of the ratchet wheel —5— and beveled at one side at —19— to permit the pawl to ride across the face of the teeth when the lever —8— is rocked in one direction without operating the ratchet wheel and when the

lever is rocked in the opposite direction to rotate the screw —4— and thereby elevate or depress both screws simultaneously, it being understood that the inner screw —6— will be held from rotation when engaged with the axle or other parts to be lifted.

The pawl —17— is provided with a laterally projecting handle —20— movable in the slots —12— and —13— and by which the 10 pawl —17— may be rocked a half revolution to reverse the same thereby causing the rotation of the ratchet wheel —5— and screw —4— in the opposite direction upon rocking the lever back and forth. That is when the 15 locking bolt —17— is rocked to one position and the lever —5— is rocked in opposite directions the screw —4— will be rotated in one direction, as for example, to elevate the screws for lifting the vehicle or other body 20 and when said pawl is reversed, the same back and forward rocking movement of the lever will cause the screws to be depressed or lowered. As the pawl —17— is rocked to one side or the other of its extreme positions, 25 it is held in such position by the interlocking of the handle —20— in the lateral offset —13— of the slot —12— where it engages opposite sides of said extension or offset —13— to prevent accidental displacement of 30 the pawl from its adjusted position, said pawl being forced to its engaging position by the spring —18— which is interposed between the shoulder on the end of the pawl and end of the socket —16—. The length of 35 the offset —13— of the slot —12— is somewhat greater than the depth of the teeth of the ratchet wheel —5— to allow a limited endwise movement of the pawl without disengaging the handle —20— from the opposite 40 site sides of the offset slot —13—.

The tubular end —9— of the lever —8— is held closely against the under side of the ratchet wheel —5— by means of a collar —25— which is fitted upon the upper end of 45 the screw —4— and held in place by a set screw —26—.

When it is desired to reverse the pawl —17— the operator simply engages the handle and forces the pawl back against the action 50 of the spring —18— until the pawl —17— is registered with the slot —12— whereupon said handle may be reversed or rocked through the slot —12— thereby reversing the pawl —17—, the spring serving to automatically force the pawl into engagement with the teeth of the ratchet wheel as soon as the arm is registered with one or the other of the recesses —13—.

The screw —14— is preferably left hand 60 pitch while the inner screw —6— is of opposite or right hand pitch which permits the lever to be operated by the right hand with a

pull and thereby with greater power to lift the load whereas if the pitch of the screws were reversed, the movement of the lever in 65 raising the load would be more or less awkward and would require such lever to be pushed by the right hand instead of pulled under which conditions the power would be somewhat less.

What I claim is:

1. In a lifting jack, a tubular upright support having its upper end reduced and threaded internally, a left hand tubular screw screwed into the upper reduced end of the 75 upright and provided at its upper end with a ratchet wheel, said upper end of the tubular screw being threaded internally, a right hand screw screwed into the upper end of the tubular screw, a rest secured to the upper 80 end of the inner screw, a lever journaled on the upper end of the tubular screw wholly under the ratchet wheel and provided with a slot opening from its top, said slot having an axial offset at its base, a straight pawl slideable axially in the lever across said slot and having its inner end beveled on one side only and its intermediate portion provided with an outwardly projecting handle movable in 85 said slot into and out of the offsets for reversing the pawl and locking it in either of its adjusted positions, and a spring for forcing said pawl into engagement with the ratchet wheel.

2. A lifting jack comprising a tubular upright support having an internally reduced threaded portion at its upper end, a tubular screw engaging said threaded portion and having its upper end provided with a ratchet wheel and a reduced internally threaded portion, an inner screw engaging the threaded portion of the tubular screw and provided at its upper end with a rest, said screws being of opposite pitch, a lever having a tubular end journaled on the upper end of the tubular screw wholly below the ratchet wheel, a collar on the tubular screw for holding the lever in proximity to the under side of the ratchet wheel, said lever being provided with an axial opening, and a transverse slot intersecting said opening, the slot being provided with an axially extending offset in the plane of the ratchet wheel, a straight sliding pawl movable in said opening and rockable therein, said pawl being provided with a handle movable in the slot into and out of the offsets for reversing the pawl and locking it in its adjusted position.

In witness whereof I have hereunto set my hand this 22nd day of October 1908.

JOTHAM B. TAYLOR.
